MEASURING TRAP CHAMBER WITH
BAROMETRIC CUTOFFThomas L. Titus, Cheyenne, Wyo., assignor to The
Wyott Manufacturing Company, Cheyenne,
Wyo., a corporation of Wyoming

Application March 10, 1945, Serial No. 581,979

3 Claims. (Cl. 222—437)

1

This invention relates to improvements in liquid dispensing devices.

It is the object of this invention to produce a simple, substantial and efficient device for dispensing liquids in predetermined quantities.

Another object of this invention is to produce a device that will operate quickly and which will be of such construction that the quantity of liquid dispensed will be very accurately measured.

Another object of this invention is to produce a device for the purpose indicated which cannot be used for abstracting more than the measured quantity of liquid at each operation.

A still further object of the invention is to produce a compact device that shall be capable of being manufactured in a pleasing and ornamental form.

Having called attention to the various objects of the invention, the invention will now be described in detail and for this purpose reference will be had to the accompanying drawing in which the invention has been illustrated in its preferred form, and in which:

Figure 1 is a vertical diameter section taken on line 1—1, Figure 2;

Figure 2 is a side elevation of the device shown in Figure 1;

Figure 3 is a fragmentary section similar to that shown in Figure 1, but shows the parts to an enlarged scale and a valve in sealing position;

Figure 4 is a fragmentary section similar to that shown in Figure 3, but shows the valve in fully opened position;

Figure 5 is a fragmentary section intended to illustrate in a clear manner the lost motion means which will be hereinafter referred to; and

Figure 6 is a view similar to Figure 5, but shows a slight modification.

In the drawing reference numeral 10 designates a support which may be of any construction; at the end of the support is a body 11 which, in the drawing, has been shown as formed integral with the support 10, but which may be, and preferably is, made from a separate piece secured to the support in any suitable manner. The under surface of body 11 has a circular depression 12 that forms a valve chamber. The upper wall of the body has a frustoconical depression 13 in its upper surface and from the vertex of this depression a fill opening 14 extends through the wall and into communication with the valve chamber. A fill tube 15 is threadedly mounted in opening 14 and projects downwardly into the valve chamber. By rotating the pipe relative to

2

the body, the position of the lower end thereof can be adjusted.

Secured to the upper end of pipe 15 is a cup 16 which may be made from rubber, either natural or synthetic, or any other suitable material. The neck 17 of the bottle or of any other liquid container, is inserted into cup 16 and the wall of the latter forms an airtight seal about the bottle neck, as clearly shown in Figure 1.

A vent 18 extends through the upper wall of the body 11. The outer surface of the valve chamber wall is threaded as indicated at 19. An end closure 20 is held in place below the valve chamber wall by means of a threaded sleeve whose lower end has an inwardly extending flange 22 that engages in a corresponding rabbet in the closure. The end closure has a downwardly extending tubular hub 23. Positioned at the lower end of the valve chamber wall is a flexible diaphragm 24 which may be made of rubber or of any other flexible material, either some suitable plastic or one of the many so-called synthetic rubbers. This diaphragm must be quite flexible and elastic and the material must be selected so that it will not be affected by the liquid being dispensed.

In the drawing, diaphragm 24 has been shown as of considerable thickness, but this is merely for convenience in drafting and explaining the invention. The diaphragm should be as thin as consistent with strength and the contemplated mode of operation. Extending through the hub 23 is a discharge tube 25 whose lower end is provided with laterally extending wings 26. The upper end of this tube is closed and has a threaded extension or stud 27 for a purpose which will presently appear. Directly beneath the upper end wall of the discharge tube, there is a groove 28 for the reception of the edge of the diaphragm 24. The diaphragm is provided with a central opening that is smaller than the bottom diameter of groove 28 so that when it is positioned as shown in Figures 2, 3 and 4, the tension exerted by the diaphragm will form a tight seal between it and the dispensing tube. The outer edge of the diaphragm is clamped between the lower end of the valve chamber wall and the upper surface of the end closure as clearly shown in the drawing. Secured to the upper end of the discharge tube is a cup having an upwardly extending wall 29. The bottom of the cup has been designated by reference numeral 30 and extending downwardly from the under surface thereof is a flange 31. The cup is provided with a central opening for the reception of the threaded stud 27 and is held in position by a nut 32. The end closure is provided

with an inwardly extending ledge 33 that has an annular concave surface 34 positioned beneath the diaphragm and directly beneath the flange 31 on the bottom of the cup. The discharge tube is provided with a plurality of openings 35 positioned directly above groove 28.

It will be observed from the drawing that the weight of the discharge tube and the cup are so related to the diaphragm and other parts that they will normally assume the position shown in Figures 1 and 3 with the flange 31 resting on the upper surface of the diaphragm. Since the diaphragm is very flexible and quite thin, the weight of these parts will bend it downwardly into engagement with the concave upper surface 15 of flange 33, as shown most clearly in Figure 5. When the parts are in normal position, like that shown in Figures 1 and 3, the plane 36 of the upper edge of the cup wall is spaced a short distance from the lower end of the fill tube 15, as 20 shown in Figure 1. It will be observed that due to the fact that the diaphragm is bent downwardly into engagement with the concave surface 34 when the weight of the parts rest on the diaphragm the seal between flange 31 and the 25 upper surface of the diaphragm will not be broken until the cup and the flange 31 have moved upwardly a distance at least equal to the distance between plane 36 and the bottom of pipe 15. This construction forms a lost motion connection 30 that permits the fill tube and cup to be moved a short distance before the seal is broken. The purpose of this is to effect a seal between the liquid in the cup and the lower end of the fill tube before the seal is broken between flange 31 and the diaphragm. As soon as the cup moves up to a position where plane 36 is in engagement with the lower end of tube 15, or slightly above it, no liquid can escape from the sealed container and therefore when the parts are moved upwardly in the position shown in Figure 4, the liquid in the valve chamber is free to escape, and during this escape period no further liquid will be supplied. When the measured quantity of liquid has been discharged and operator relieves the pressure on the lower end of the discharge tube, the latter falls, due to the action of gravity and before the plane 36 passes below the end of the fill tube 15, a seal is effected between the diaphragm and flange 31. The construction just described assures that no liquid can be surreptitiously removed by the expedient of carefully and slowly moving the valve to closed position.

In Figure 6 a slightly modified form of construction has been shown in which the flange 31, instead of being made entirely of metal is 31a made in part of a resilient flexible material which bends when it comes in contact with the diaphragm and thus gives a lost motion effect similar to that obtained by the construction shown in Figure 5.

This device is intended to be connected with an automatic counting mechanism that indicates the number of times the discharge valve has been moved upwardly and therefore an operator will be charged with the total quantity of liquid, even if the valve chamber is only partly full at the time the valve is opened.

The feature just described is a safety feature of great importance where expensive liquids are being dispensed as it discourages attempts to cheat and in fact makes it impossible to do so.

It will be observed that added to the weight of the discharge tube and the cup is the weight of the liquid in the cup which serves to set the

valve. The weight of the liquid in the cup will, of course, be counterbalanced or made ineffective when the cup is surrounded by liquid as in Figure 1.

In the above description a lost motion connection has been shown and described which is simple and effective for the purpose under consideration, but it is to be understood that this is merely illustrative of means for this purpose and that it may be replaced by some equivalent lost motion construction that will effect a seal of the intake tube before the valve is opened and a closing of the valve before the intake is unsealed, thus assuring that no liquid will be supplied to the valve chamber at any time when the seal between flange 31 and the diaphragm is broken.

Attention is again called to the fact that the diaphragm has been shown to an exaggerated thickness and it is to be understood that it is to be as thin as can practically be used so as to afford as little resistance towards flexure in response to the weight of the parts as possible.

Having described the invention what is claimed as new is:

1. A device for dispensing liquid in measured quantities, comprising, a body having a valve chamber, provided with a fill opening and a vent in its upper wall, a fill tube in the fill opening, the fill tube projecting below the upper wall surface of the chamber, an airtight liquid container above the body in communication with the fill tube through an opening in its bottom, the lower end wall of the chamber having a discharge opening, a discharge tube extending through the discharge opening, the upper end of said tube being closed, a flexible diaphragm having a central opening through which the discharge tube extends, means for attaching the outer edge of the diaphragm to the wall of the valve chamber, the wall of the discharge tube having an opening above the diaphragm, a cup secured to the upper end of the discharge tube, below the lower end of the fill tube, the under surface of the cup having an annular flange positioned to engage the upper surface of the diaphragm to form a seal, the parts being so proportioned and related that when the flange is in normal sealing position the plane of the upper edge of the cup will be spaced a short distance below the lower end of the fill tube, the cup being movable upwardly to a point where the plane of its upper edge is above the lower end of the fill tube before the seal between the flange and the diaphragm is broken, whereby air is prevented from entering the container until the flange returns to sealing position.

2. A device for dispensing liquid in measured quantities, comprising, a body having a valve chamber provided with a fill opening in its upper wall, an airtight liquid container positioned above the body, the opening in the upper wall being formed in part by a fill tube that projects downwardly into the valve chamber, the container communicating with the chamber through the fill tube, the lower wall of the chamber having a discharge opening, a discharge valve comprising a discharge tube having its upper end closed, extending through the discharge opening, a flexible diaphragm having a central opening for the reception of the discharge tube and connected therewith by a watertight seal, the wall of the discharge tube having openings positioned above the diaphragm, means for effecting a seal between the wall of the chamber and the outer

edge of the diaphragm, and a cup connected with the upper end of the discharge tube, the cup opening upwardly and positioned beneath the fill tube, the under surface of the cup having a circular flange adapted to engage the upper surface of the diaphragm to form a seal, the relationship of the parts being such that when the cup and discharge tube are supported from the diaphragm, the lower end of the fill tube will be a short distance above the plane of the upper end of the cup, the upper wall of the valve chamber having a vent.

3. A device for dispensing liquid in measured quantities from a sealed container having a discharge opening in its under side, comprising, in combination, a body having a valve chamber in its under surface, a removable end closure for the chamber, the end closure having an opening, a discharge tube in said opening, the upper end of the tube being closed, a cup supported from the upper end of the tube, a flexible diaphragm

extending from the tube to the wall of the valve chamber in sealing relation with both, the wall of the discharge tube having at least one opening positioned above the diaphragm, the upper wall of the valve chamber having an opening positioned within the area of the cup, a fill pipe threadedly engaging the wall of the last named opening, the interior of the sealed container being in communication with the valve chamber through the fill pipe, the under surface of the cup having an annular flange for engaging the upper surface of the diaphragm, the parts being so related that when the cup and discharge tube are supported from the diaphragm, the top of the cup will be a short distance below the lower end of the fill tube, and will be above the lower end of the fill tube before the seal between the flange on the cup and the diaphragm is broken, whereby no liquid will flow from the sealed container while the valve is open.
